**ORGANIZED APPOINTMENT BOOK FOR A
HAIRSTYLIST**

BACKGROUND OF THE INVENTION

1. Field of the Invention

The instant invention relates generally to calendar schedule devices and more specifically it relates to an organizer guide book.

2. Description of the Prior Art

Numerous calendar schedule devices have been provided in prior art. For example, U.S. Pat. Nos. 2,505,417 to Maline; 4,043,063 to Ambasz; 5,030,027 to Bachrach et al. and 5,387,011 to Freund all are illustrative of such prior art. While these units may be suitable for the particular purpose to which they address, they would not be as suitable for the purposes of the present invention as heretofore described.

MALINE, CHARLES

DESK CALENDAR PAD

U.S. Pat. No. 2,505,417

A desk calendar pad that specifically pertains to an accessory for a desk, which provides an annual calendar and a memorandum pad in roll form. It is for conveniently presenting calendar data together with a memorandum pad surface for each of the days of a year in chronological sequence.

AMBASZ, EMILIO

APPOINTMENT CALENDAR BOOK

U.S. Pat. No. 4,043,063

An appointment calendar comprises a ring-type binder, at least one page having a pocket and a flap which partially slips into the pocket, and an insertion having two leaves, one of the leaves being received in the pocket to hold the insertion in place in the calendar and the other leaf, which contains printed promotional, decorative or informative matter, overlying the pocket so that the printed matter is visible. The pocket is closed along all margins except along an opening adjacent the edge of the page that is engaged in the binder. The binder rings engage the flap and a part of the page which is non-pocketed but do not engage the pocket or the insertion.

BACHRACH, SCOTT

BACKUS, ALAN L.

SCHEDULE AND PAPERWORK ORGANIZER

U.S. Pat. No. 5,030,027

A device to facilitate organization of educational and business schedules and paperwork, simultaneous with conveying varied graphic and social images. The device is a ring binder in which a time piece is mounted for easily viewing the time display. A pocket is provided on the front cover of the device for receiving and easily changing opaque and transparent imprinted sheets to alter appearance, while exposing the time display.

FREUND, WILLIAM D.

SYSTEM AND METHOD FOR SCHEDULING A
MEETING

U.S. Pat. No. 5,387,011

A system and method for scheduling a meeting uses several partially translucent sheets, one for each prospective

attendee. Each partially translucent sheet contains an array of blocks of time, in which the rows correspond to time periods and the columns correspond to dates. The prospective attendee darkens the blocks corresponding to times that he is not available to attend the meeting, and sends the completed sheet to the organizer. The organizer then assembles the sheets, and stacks and aligns them so that the blocks line up. By viewing the stack of partially translucent sheets, preferably with a light source, the organizer can quickly identify the times when all prospective attendees are available for the meeting by identifying those blocks that remain translucent. If each prospective attendee uses the same type of writing apparatus so that the intensity of the darkened blocks is consistent among all the prospective attendees, then when the organizer assembles the sheets, if no time is available that all prospective attendees can meet, the next best time and date is the block that appears lightest. This allows the organizer to identify the times that the most people can attend the meeting, and not just the time when everyone can attend the meeting.

SUMMARY OF THE INVENTION

A primary object of the present invention is to provide an organize appointment book for a hairstylist that will overcome the shortcomings of the prior art devices.

Another object is to provide an organize appointment book for a hairstylist that is a loose-leaf binder constructed to hold imprinted pages that can be especially used by the hairstylist, to book future clients more efficiently.

An additional object is to provide an organize appointment book for a hairstylist that will hold additional imprinted pages for addresses and telephone numbers, important dates, a reorder reminder, a reorder form and a price list to help aid the hairstylist.

A further object is to provide an organize appointment book for a hairstylist that is simple and easy to use.

A still further object is to provide an organize appointment book for a hairstylist that is economical in cost to manufacture.

Further objects of the invention will appear as the description proceeds.

To the accomplishment of the above and related objects, this invention may be embodied in the form illustrated in the accompanying drawings, attention being called to the fact, however, that the drawings are illustrative only, and that changes may be made in the specific construction illustrated and described within the scope of the appended claims.

**50 BRIEF DESCRIPTION OF THE DRAWING
FIGURES**

Various other objects, features and attendant advantages of the present invention will become more fully appreciated as the same becomes better understood when considered in conjunction with the accompanying drawings, in which like reference characters designate the same or similar parts throughout the several views, and wherein:

FIG. 1 is a perspective view showing two of the instant invention in closed positions on a counter in a hairstyling store.

FIG. 2 is a perspective view taken in the direction of arrow 2 in FIG. 1, showing an imprinted name tag ready to be inserted into a transparent pocket on a spine of a loose-leaf binder.

FIG. 3 is a perspective view of the instant invention in an opened position upon the counter.

FIG. 4 is a plan view with parts broken away of a client booking sheet for a hairstylist with an assistant.

FIG. 4a is a plan view with parts broken away of an alternate client booking sheet for just the hairstylist.

FIG. 5 is a plan view with parts broken away of an address and telephone numbers sheet.

FIG. 6 is a plan view with parts broken away of an important dates sheet.

FIG. 7 is a plan view with parts broken away of an order reminder sheet.

FIG. 7a is a plan view with parts broken away of an alternate order reminder sheet.

FIG. 8 is a plan view with parts broken away of an order form sheet.

FIG. 8a is a plan view with parts broken away of an alternate order form sheet.

FIG. 9 is a plan view with parts broken away of a price list sheet.

Similar reference characters denote corresponding features consistently throughout the attached drawings.

DETAILED DESCRIPTION OF THE PREFERRED EMBODIMENTS

Turning now descriptively to the drawings, in which similar reference characters denote similar elements throughout the several views, FIGS. 1 to 3 illustrate an organize appointment book for a hairstylist 10 comprising a loose-leaf binder 12 having a front cover 14 and back cover 16 hinged to a spine 18. A page holder 20 is mounted to the spine 18.

A plurality of imprinted pages 22 are detachably held by the page holder 20. Each imprinted page 22 bears printed indicia 24 thereon for providing information to the hairstylist using the organize appointment book for a hairstylist 10.

The page holder 20 includes a longitudinal base mechanism 26 connected to an inner surface of the spine 18. A plurality of openable ring connectors 28 are spaced apart and transversely connected to the base mechanism 26, to engage with openings 30 in a margin 32 of each imprinted page 22. A plurality of index tab dividers 34 are each attachably held by the page holder 20 between the imprinted pages 22, so as to arrange in monthly order the imprinted pages 22 within the loose-leaf binder 12.

A transparent side pocket 36 is on an outer surface of the spine 18. An imprinted name tag 38 of the hairstylist can be inserted into the transparent side pocket 36. A transparent front pocket 40 is on an outer surface of the front cover 14. A graphically imprinted sheet 42 can be inserted into the transparent front pocket 40.

One of the imprinted pages 22, as best shown in FIG. 4, is a client booking sheet 44 for the hairstylist with an assistant. One of the imprinted pages 22, as best seen in FIG. 4a, is a client booking sheet 46 for just the hairstylist. One of the imprinted pages 22, as best seen in FIG. 5, is an addresses and telephone numbers sheet 48.

One of the imprinted pages 22, as best seen in FIG. 6, is an important dates sheet 50. One of the imprinted pages 22, as best seen in FIGS. 7 and 7a, is a reorder reminder sheet 52. One of the imprinted pages 22, as best seen in FIGS. 8 and 8a, is an order form sheet 54. One of the imprinted pages 22, as best seen in FIG. 9, is a price list sheet 56.

The client booking sheet 44 for the hairstylist with an assistant in FIG. 4 and the client booking sheet 46 for just the hairstylist in FIG. 4a, both consist of an hourly sched-

uling calendar and are preprinted replaceable schedule sheets. The client booking sheet 44, as shown in FIG. 4, has four columns, which are from left to right. A first column for phone numbers (home and work), a second column for the hairstylist's clients names, a third column for the assistant's clients names and a fourth column for stand by appointments. The client booking sheet 44a in FIG. 4a, is similar to FIG. 4, but has three columns instead of four columns, with the column for the assistant's clients names eliminated therefrom. The addresses and telephone numbers sheet 48 in FIG. 5, has room for a plurality of names, addresses and telephone listings thereon. The important dates sheet in FIG. 6, lists all of the holidays of the year and their dates.

The reorder reminder sheet 52 in FIGS. 7 and 7a indicates the month, such as in September, for ordering a new organize appointment book 10 for the next year that is coming up. The order form sheet 54 in FIGS. 8 and 8a, can be filled out and sent in for the new order. The price list sheet 56 in FIG. 9, indicates prices for various hairstyling services and times available for the booking.

The imprinted name tag 38 that is inserted into the transparent side pocket 36 is the name of the hairstylist that will use it. The graphically imprinted sheet 42 for the transparent front pocket 40 can be changeable art, of any picture you want.

The loose-leaf binder 12 can come in different colors. There can also be an imprinted page at the back of the loose-leaf binder 12, to indicate major hair shows throughout the United States. A plastic card holder sheet the size of the imprinted pages 22 can be inserted into the loose-leaf binder 12, to hold various business cards of suppliers, vendors, etc. A clear plastic page marker can be provided, to drop down from a top left side and cover or hold an imprinted page 22 on the left side to act as a quick book marker.

It will be understood that each of the elements described above, or two or more together may also find a useful application in other types of methods differing from the type described above.

While certain novel features of this invention have been shown and described are pointed out in the annexed claims, it is not intended to be limited to the details above, since it will be understood that various omissions, modifications, substitutions and changes in the forms and details of the device illustrated and in its operation can be made by those skilled in the art without departing in any way from the spirit of the present invention.

Without further analysis, the foregoing will so fully reveal the gist of the present invention that others can, by applying current knowledge, readily adapt it for various applications without omitting features that, from the standpoint of prior art, fairly constitute essential characteristics of the generic or specific aspects of this invention.

What is claimed is new and desired to be protected by Letters Patent is set forth in the appended claims:

1. An organize appointment book for a hairstylist comprising:

- a) a loose-leaf binder having a front cover and back cover hinged to a spine;
- b) a page holder mounted to said spine comprising a longitudinal base mechanism connected to an inner surface of said spine and a plurality of openable ring connectors spaced apart and transversely connected to said base mechanism to engage with openings in a margin of each said imprinted page;
